UNITED STATES PATENT OFFICE.

HORACE S. ROSSER, OF NORFOLK, VIRGINIA.

PISTON-PACKING.

1,300,197.

Specification of Letters Patent.

Patented Apr. 8, 1919.

Application filed October 20, 1917. Serial No. 197,655.

To all whom it may concern:

Be it known that I, HORACE S. ROSSER, a citizen of the United States, residing at Norfolk, in the county of Norfolk and State of 5 Virginia, have invented new and useful Improvements in Piston-Packings, of which the following is a specification.

This invention relates to new and useful improvements in packing means for piston rods, valve stems and the like, and the principal object of the invention is to provide a packing which will reduce the leakage past the stem to a minimum and at the same time will not be easily broken and will have the 15 maximum wearing qualities.

Another object of the invention is to form a packing having a combination of alloy and cast iron of proper proportions, so that alloy will act as an anti-friction metal and prevent undue wear to piston rod stem. The 20 cast iron is to prevent undue wear to alloy, strengthen segments and reinforce laps to prevent breakage.

A further object of the invention is to 25 make the packing of a plurality of segments, provided with overlapping portions, and to so locate the inserts that the said laps are strengthened thereby.

Another object of the invention is to 30 provide a device of this character which is simple and durable in construction, reliable and efficient in operation and one which can be manufactured and placed upon the market at a minimum cost.

35 The invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is a longitudinal section of a stuffing box embodying my invention.

Fig. 2 is a front view of the segmental packing assembled but with the springs omitted.

Fig. 3 is a part side view thereof showing the laps.

Figs. 4, 5 and 6 are details of the cover plate.

55 Fig. 7 is a front view of the push ring.

Fig. 8 shows a pair of cast iron inserts.

Fig. 9 is a front view of the split spring for holding the parts assembled.

In Fig. 1 part of the piston or valve rod is represented at 1, this rod being surrounded 60 by the stuffing box casing indicated at 2 and containing the improved packing forming the subject matter of my invention. This packing consists of the ring 3 made up of a plurality of segments 4, three of such segments being shown in the drawings. At the meeting ends said segments are provided with overlapping portions 5, as shown in Figs. 2 and 3, and said overlapping ends are covered by a cover plate 6. This cover plate 65 is provided with a pair of downwardly projecting lugs 7 which are adapted to fit in recesses 8 formed on one of the segments whereby said cover plate is secured to one segment but has sliding movement on the other segment. The projecting lugs 7 may be of square formation or may have an inclined front face. In this manner the recess 70 80 85 90 95 100 105 110

8 is separated from the cut-away portion at the end of the segment. I form a pair of slots 10 in the outer face of the cover plate which are adapted to receive the split circular springs 11 which holds the parts in assembled position. The outer edges of the cover plate are inclined as at 12 and I prefer to form a recess 13 in the outer periphery of the segment at that end which has sliding contact with the cover plate. The other end of the segment is also recessed so that the cover plate is slightly countersunk therein. Each segment is provided with a dowel slot 14 in its rear face, substantially mid-way of its ends, and these slots are adapted to receive the wedge-shaped lugs 15 projecting from the push ring 16 which engages the said rear face of the segments. An extension 17 is formed on the opposite face of said ring which is adapted to receive the coil spring 18 which is compressed between said push ring and the end of the casing. Thus the segmental ring is held against the front of the casing as clearly shown in Fig. 1.

After the parts are assembled the springs 11 are placed around the same and said springs are seated in the grooves 10 of the cover plates, thus said springs tend to reduce the diameter of the segmental ring by forcing the segments thereof together and thus cause said ring to grip the rod.

In carrying out my invention I prefer to form each segment of an alloy, such as a mixture of copper, tin and lead, combined with cast iron inserts. These inserts are indicated by the reference numeral 20 and I prefer to provide these inserts with openings 21 on both sides and to machine them and then the alloy is cast around them. I so position the two inserts that the end of one of them will project into one of the laps of the segment at one end while the end of the other insert will project into the lap at the other end of the segment so as to strengthen said laps. It will be seen that the inserts are so located that the inner peripheries are exposed and will come in contact with the rod, said inserts being arranged one in front of the other but spaced apart so that the alloy is between them.

My improved die casted alloy packing with cast iron ring inserts is so designed as to make all the joints steam tight with a sufficient amount of lap to allow for long wear before it is necessary to adjust the segments and said packing will act as an anti-friction means to prevent excessive wear of the piston rod. The iron inserts will prevent undue wear to the alloy and by having their ends projecting into the laps, the said laps are prevented from breaking.

It is thought from the foregoing description that the advantages and novel features of my invention will be readily apparent.

I desire it to be understood that I may make slight changes in the construction and in the combination and arrangement of the several parts, provided that such changes fall within the scope of the appended claims.

What I claim is:—

1. A packing of the class described comprising a body composed of an alloy and a pair of cast iron rings in said body spaced apart, said body and rings made up of segments having overlapping ends, the end of one ring projecting into the lap at one end of the body and the other ring into the lap at the other end.

2. A packing of the class described comprising a ring made up of segments having overlapping ends, one end of each segment having a recess therein adapted to receive a lug on one side of a cover plate, the other end of said cover plate having sliding engagement with the other segment and each of said segments having a slot in its rear face for engagement with a lug on a push ring.

In testimony whereof I affix my signature.
HORACE S. ROSSER.
